UNITED STATES PATENT OFFICE.

LOUIS A. PIAGET, OF PATERSON, NEW JERSEY.

DESIGN FOR A BADGE.

SPECIFICATION forming part of Design No. 21,642, dated June 21, 1892.

Application filed April 18, 1892. Serial No. 429,683. Term of patent 3½ years.

To all whom it may concern:

Be it known that I, LOUIS A. PIAGET, a citizen of the United States, residing at Paterson, in the county of Passaic and State of New Jersey, have invented and produced a new and original Design for a Badge for the celebration of the city of Paterson, New Jersey, of which the following is a specification, reference being had to the accompanying drawings, forming part thereof—

Figure 1 is a front view of badge, and Fig. 2 is a view showing reverse side of medal.

The leading feature of my design consists in a badge, the front having the representation of a locomotive and the Passaic Falls in the center. Outside of this is an outer circle with thirteen points representing the thirteen original States and at the top of the circle a space for dates, the whole suspended by a ribbon from a bar, on the front

of which is a space for suitable inscription. On the center of the bar at top is a mulberry-leaf, and on it the representation of a silk-worm, and over each end of the bar the representation of a skein of silk, and beneath the center of the bar a butterfly with outspread wings. On the reverse side of the medal is a bust representing Alexander Hamilton, beneath which is space for a name and above which is a panel for a motto.

30

In the drawings, A represents the medal, B the ribbon, and C the bar.

I claim—

The design for a badge, as herein shown and described.

LOUIS A. PIAGET.
